UNITED STATES PATENT OFFICE.

GEORGE G. SCARBOROUGH, OF GIRDLETREE, MARYLAND.

HEATING-STOVE.

1,343,645.

Specification of Letters Patent.

Patented June 15, 1920.

Application filed May 2, 1919. Serial No. 294,243.

To all whom it may concern:

Be it known that I, GEORGE G. SCARBOROUGH, a citizen of the United States, residing at Girdletree, in the county of 5 Worcester and State of Maryland, have invented certain new and useful Improvements in Heating-Stoves, of which the following is a specification.

My invention relates to improvements in 10 heating stoves.

An important object of the invention is to provide a stove of the above-mentioned character, formed in few and simple parts, which are readily separated for the purpose of 15 shipment, and may be quickly and conveniently assembled.

A further object of the invention is to provide a stove of the above-mentioned character, having a magazine feed for the 20 fuel, such as coal or the like, together with means to prevent the fuel being subjected to the action of excessive heat, for a substantial period, prior to its introduction into the fire box of the stove.

25 A further object of the invention is to provide a stove of the above-mentioned character, which is simple in construction, inexpensive to manufacture, strong and durable.

Other objects and advantages of the invention 30 will be apparent during the course of the following description.

In the accompanying drawings forming a part of this specification, and in which like numerals are employed to designate like 35 parts throughout the same:

Figure 1 is a central vertical longitudinal sectional view through a stove embodying my invention;

Fig. 2 is a horizontal sectional view, taken 40 on line 2—2 of Fig. 1;

Fig. 3 is a similar view, taken on line 3—3 of Fig. 1;

Fig. 4 is a perspective view of an inner shell included in the stove;

Fig. 5 is a similar view of a sealing ring or washer;

Fig. 6 is a similar view of an annular cap or cover; and,

Fig. 7 is a similar view of a fuel feeding magazine.

In the drawings, wherein for the purpose of illustration is shown a preferred embodiment of my invention, the numeral 10 designates a cylindrical body portion, having a 5 grate 11, which divides the same into an upper fire-box 12 and a lower ash-pit 13. The

body portion 10 is supported by legs 14, and a swinging door 15 controls access to the ash-pit and may be employed to regulate the entrance of air beneath the grate 11. 60

At its upper end, the body portion 10 is provided with an annular heat absorbing and radiating element 16, having a substantially thick cross sectional area. This element has a lower inclined face 17, and is provided with an upstanding annular flange 18. 65

The numeral 19 designates a doubled wall casing, arranged upon the element 16, and embodying an outer cylindrical shell 20, snugly receiving the annular flange 18, and 70 forming therewith a gas-tight joint. This doubled wall casing further comprises an inner cylindrical shell 21, having a substantially smaller diameter, providing an annular passage 22 for the escape of the heated 75 gases and products of combustion. This inner shell 21 has a bottom 23, while its top is open and is adapted to be covered by an annular lid 24, adapted to seat upon the upper edge of the shell 21. The inner shell 21 is 80 provided near its lower end with combined supporting and spacing bars 26, rigidly secured thereto, and projecting downwardly beyond the same to rest upon the flange 18.

The numeral 27 designates a preferably 85 vertical tubular fuel feeding magazine, extending longitudinally through the inner shell 21, and through an opening 28, in the bottom 23 of the inner shell 21. The magazine 27 fits loosely in the opening 28 and is 90 provided with an annular flange 29 contacting with the bottom, to support the magazine, and closing the opening 28, thereby effecting a gas-tight joint between the magazine 27 and the bottom 23. The lower end 95 of the tubular magazine 27 projects into the upper end of the fire-box 12, as shown. The upper end of the tubular magazine 27 extends through an opening 30, formed in the lid 24, and this opening is preferably larger 100 in diameter than the magazine. The opening 30 is covered by a sealing ring or washer 31, snugly receiving the upper end of the magazine 27, and slidably contacting with the upper surface of the lid 24. Particular 105 attention is called to the fact that the magazine 27 has a much smaller diameter than the inner shell 21, thereby providing a dead air chamber 32 which is annular in horizontal cross section and surrounds the magazine 110 27, such space 32 having a substantial cross sectional area and serving as effective heat

insulating means between the magazine 27 and the passage 22. It is thus seen that the coal or fuel within the upper portion of the magazine 27 will not be subjected to excessive heat, for effecting its destructive distillation, for a substantial period, prior to its discharge from the lower end of the magazine, into the fire-box. The fuel in the lower portion of the magazine substantially closes the same thereby protecting the fuel in the upper portion, from excessive heat. As the fuel in the fire-box is consumed, the fuel in the magazine automatically works downwardly.

15 The numeral 32' designates a top, of annular form, and preferably curved in cross section. The outer edge 33 of this top receives the upper end of the outer shell 20, and is clamped thereto by bolts 34 or the like. The inner tubular portion 35 of the top 32' snugly receives the upper end of the tubular magazine. The top of this tubular portion is open and is normally covered by a lid 36, detachably engaging an annular flange 37, such lid being preferably equipped with a handle 38. The cover 32' is provided outwardly of its tubular portion 35 with a tubular coupling 39, adapted for connection with a stove pipe 40, in communication with the passage 22, for the escape of the products of combustion.

35 In the use of the stove, the fire is built in the fire-box 12, and the fuel for this purpose may be introduced through the magazine 27. After the fire is started, coal or the like is fed into the magazine 27, until the fire-box is substantially filled with the coal and the tubular magazine is also substantially filled. The products of combustion or 40 heated gases discharge through the passage 22 of the doubled wall casing 19, and

through the stove pipe 40 to the atmosphere. The chamber 32 serves to effectively insulate the tubular magazine 27 by the passage 22. The coal in the lower end of the magazine substantially closes the same, thereby preventing the products of combustion traveling upwardly therein, and protecting the coal in the upper portion thereof from the action of excessive heat, which would tend to effect its destructive distillation.

45 It is to be understood that the form of my invention herewith shown and described is to be taken as the preferred example of the same, and that various changes in the shape, size, and arrangement of parts may be resorted to without departing from the spirit of my invention or the scope of the subjoined claim.

55 Having thus described my invention, I claim:

In a self-feeding stove, the combination with an outer shell and an inner shell arranged within the outer shell and spaced therefrom, said inner shell being provided with a bottom having a central opening and a cover for said inner shell, said cover being provided with an opening in alignment with the bottom opening, of a fuel magazine arranged within said inner shell and projecting beyond the ends thereof, said magazine being provided with a flange adapted to rest upon the bottom of said inner shell to support the magazine, a sealing ring snugly fitting said magazine and resting on said cover, a top having an outer flange to engage said outer shell and an inner flange to receive said magazine and maintain it in position, and a cover for said magazine resting on said top.

65 70 75 80 In testimony whereof I affix my signature.
GEORGE G. SCARBOROUGH.
